UNITED STATES PATENT OFFICE

WILLIAM M. SCHOLL, OF CHICAGO, ILLINOIS

ARCH SUPPORT

Application filed May 26, 1924. Serial No. 715,839.

The invention relates to improvements in arch supports.

One of the objects of the invention is to provide a support for the arches of the foot so formed that it tends to restore and maintain the plantar surface of the foot to and in its natural form.

Another object is to provide a foot support which will produce a substantially uniform distribution of the weight imposed upon the foot over the plantar area thereof, after the parts of the foot have been restored to their natural positions.

A further object is to provide an arch support which is light, elastic, comfortable and sufficiently stable to perform the foot comforting and correcting functions for which it is designed. It is especially suitable to be worn in the modern, light-weight, fashionable fragile foot wear designed for women and possesses qualities which render it desirable for use in children's shoes.

Other objects, advantages and benefits will readily appear from a consideration of the following description when taken in conjunction with the accompanying drawings forming a part hereof, wherein:

Fig. 1 is a bottom plan view of the device showing a part of the covering removed.

Fig. 2 is a plan view of an inner spring plate with attached lining sheet.

Fig. 3 is a plan view of the yielding or resilient plastic pad for raising the second, third and fourth metatarsal bones of the anterior or metatarsal arch of the foot.

Fig. 4 is a longitudinal central section thru Fig. 1.

Fig. 5 is a transverse section on line 5—5 thru Fig. 1.

Fig. 6 is a section taken on line 6—6 of Fig. 1.

In all the views the same reference characters are employed to indicate corresponding parts.

A device suitable for the purpose intended must be characterized by lightness, strength, elasticity and of suitable configuration to conform the parts of the foot to their natural respective reposing positions without exert-

ing localized excessive pressure after the restoration has been accomplished.

In the drawings 10 represents a leather sole or tap, fan-flared at 11 near its front end and skived in a round area at 12 at the heel end. This end is skived to provide a cavity to receive the oscalcis of the foot. This top piece or tap conforms to the plantar surface of the foot and with the underlying elements provides means for supporting and replacing the structures known as the inner and outer longitudinal arch and the anterior transverse metatarsal arch. The appliance restores the foot to its normal three point bearings:—the oscalcis, first metatarsophalangeal joint, and fifth metatarsophalangeal joint.

The cavity 12 formed by skiving the leather provides a receptacle for the heel of the foot, thus supporting the oscalcis and the tender sensitive tissues attached to that part of the bone structure. This is brought about by the surrounding elevation 13 which relieves the aforesaid parts of the pressure which otherwise would be impressed thereupon by transferring the pressure to the part 13 and substantially suspending the sensitive parts within the cavity 12. This furthermore permits the heel portion of the foot to extend more deeply into the shoe and thereby prevents the shoe from pulling off at the heel due to the elevation of the foot within the shoe being increased by the thickness of the device at this point.

The more-or-less rigid, yet yielding supporting element of the structure, the metal spring blade 14, is substantially straight along the inner longitudinal edge 15 and curves outwardly at 16 from the heel end and extends forwardly into a fan-like part 17 at its forward end to provide a base of support for the anterior, metatarsal correction pad 18.

The pad 18 of a yielding, resilient nature, may be made of such material as felt, curled hair, sponge rubber, composition cork, or the like. It is supported upon the forward, fan-shaped end 17 of the underlying spring plate 14. The pad is of proper outline, as shown, to support and to elevate the displaced sec-

ond, third and fourth metatarsal bones ante-
riorly.

The device is designed and intended to re-
5 store the parts of the foot to its normal three
point bearings, the oscalcis, the first meta-
tarsophalangeal joint and the fifth meta-
tarsophalangeal joint and, when these parts
are in their natural position, the pressure
10 upon the plantar surface of the foot is sub-
stantially evenly distributed upon the sup-
port.

By skiving the edges of the tap or sole 10
at 20 to taper it toward the edge and at 21 in
the same manner, the abruptness of these
15 surfaces is avoided and the supporting func-
tion for the transverse arch is more pro-
nounced.

The spring may be suitably and securely
20 fastened to a thin leather sheet 22 in any suit-
able manner and the sheet 22 may then be
secured to the tap plate 10 by cement, stitch-
ing or the like, and the rivets embedding in
the tap 10 thus avoid presentation of rough
disagreeable surfaces to the foot.

25 The bottom surface of the device may be
covered with soft leather, chamois, felt fab-
ric 23, or the like, by stitching, cement, or
other unobjectionable means.

Having described my invention what I
30 claim as new and desire to secure by Letters
Patent, is:—

As an article of manufacture, an arch sup-
port including a sole member having on its
upper surface at its rear portion a skived re-
cess therein, adapted to be disposed below
35 the oscalcis of the foot of the wearer, sur-
rounded by a marginal area of substantial
width, a substantially oval-shaped yieldable
pad adjacent the forward end of said mem-
ber having a widened forward portion to
40 underlie the second, third, and fourth meta-
tarsophalangeal joints of the foot, a longitudi-
nally arched spring plate underlying the
sole member and supporting the longitudi-
45 nal arch of the foot, said plate extending for-
ward beneath the yieldable pad and support-
ing the plantar surface of the foot, and a
lower covering member disposed below the
50 pad and spring plate and protecting these
members from contact with the shoe sole.

In testimony whereof I hereunto set my
hand.

WILLIAM M. SCHOLL.
